METHOD AND MEANS FOR THE RECORDATION OF SOUND

Carl Louis Oswald, New York, N. Y., and Warren Dunham Foster, Washington Township, Bergen County, N. J., assignors, by direct and mesne assignments, to Kinatome Patents Corporation, a corporation of New York

Original application October 29, 1928, Serial No. 315,761, now Patent No. 1,928,392, dated September 26, 1933. Divided and this application August 21, 1933, Serial No. 686,154. In Great Britain October 26, 1929

21 Claims. (Cl. 179—100.3)

The present invention relates broadly to the art of recording sound upon light sensitive material by photo electrical means, but it will be readily understood that it may be applied to many other uses. Our invention is applicable for recordation of sound images alone or sound images in conjunction with visual images, as in the so called "talking movies".

The present application is a division of our pending application Serial Number 315,761, filed October 29, 1928.

A primary object of our invention is to secure the accurate and faithful translation of sound waves into photographic images. We provide improved method and means whereby sound may be recorded more accurately than heretofore has been possible, either independently or in conjunction with pictures.

A related object is the photographing upon film from which sound is to be reproduced, of lines or masses which are so clear and distinct, and of such uniform density, that sound waves reproduced from them will be clear, distinct and true.

In the past, attempts to secure such clear and uniform photographic images have led to the adoption of various expedients which in turn have led to difficulties. One common plan has been the use of a slot so narrow that only with difficulty can it be constructed with sufficient accuracy for practical efficiency. In many cases, the film has been fed in close physical contact with the medium containing the slot, thus rapidly filling the slot with dirt, dust, and portions of emulsion or cellulose from the film, and also putting an undue strain upon the film. While we provide a satisfactory means for the construction of a slot of extremely small width and for keeping it free from obstructions as is claimed in our parent patent, in apparatus constructed according to certain of the preferred forms of our invention it is not necessary to provide a slot of such extreme narrowness or to run the film in actual contact with the material forming or covering the slot.

Under current practice, it has been thought necessary to restrict the area of the effective image formed by the sound which is being recorded to the exact area of the slot through which the actuating light passes, thus creating obvious restrictions. In apparatus constructed according to a preferred form of our invention, the area of the effective image may be materially smaller than that of the slot, and in that made according to another preferred form it may be slightly larger.

Another object of our invention is to make possible the use of photographic images in lines or mass formations, representing sounds which it is desired to record for reproduction, which photographic images may be materially smaller than such as now are common in the art. We are able by such means to make use of many more sound images or tone symbols in a given length of film, greatly increasing its tonal time equivalent and range and consequently also greatly augmenting the effectiveness, in a given time period of combined sound and picture reproduction. Moreover, our invention has particular usefulness in connection with motion picture and phonograph apparatus which employs films of 16 millimeters or 9 millimeters in width or of some other size primarily designed for home use and which are of less than the so called theatrical standard of 35 millimeters width. Obviously upon such films, which, because of economy and other commercial conditions, are now well established for domestic use, the area which is available for the sound image is very much reduced. As a consequence the difficulties which have arisen from ill defined photographic images, representing sound impulses, when these are imprinted upon 35 millimeter film, have been greatly exaggerated when such images have been correspondingly reduced in size for use upon 16 millimeter or other so called sub-standard films. Our invention makes it possible to secure upon 16 millimeter film, for example, as clear and accurate sound images as those which previously have been secured upon 35 millimeter film, and can be applied with corresponding effect to films of even 35 smaller dimensions.

Under present practice, inaccurate and consequently unpleasant sound reproductions have resulted from undesired fluctuations in the theoretically constant light source of the recording apparatus. Our invention includes means for obviating such difficulties.

Another object of our invention is to add to the electrical and acoustic means commonly employed in the recordation of sound images certain photographic methods, means and technique in such manner as to secure improvement in the quality of sound translation and subsequent retranslation. By the employment of the apparatus and the means and methods herein described, it is possible to assure the integrity of the latent sound image as of the moment at which it is implanted upon the photo-sensitive material. A further object of our invention is the treatment of that latent image by such

chemical and physical means, chosen with due regard to the means and methods which had been employed to implant the latent image and the characteristics of the particular photo-sensitive material employed, as will retain in the stable and completed sound image the quality imparted by such previous steps in the process.

Another object of our invention is to provide apparatus for the taking of talking pictures or of films for film playing phonographs, which may be simply constructed and maintained.

Other objects, advantages and characteristics of our invention are apparent from the following description, the attached drawings and the subjoined claims. Although we are showing one preferred embodiment of each of the several phases of our invention, it will be readily understood that we are not limited to these particular constructions and processes as changes can be readily made without departing from the spirit of the invention or the scope of our broader claims.

It will be readily understood by those skilled in the art that our invention applies to sound apparatus generically. It will also be readily understood that our invention may be applied to any art in which the accurate and controlled recordation of a photographic image is useful or necessary in the exercise of control or translation by means of light.

In the drawings:

Figure 1 is a diagrammatic representation of diffraction occurring as light passes through an aperture, greatly exaggerated for the purpose of clarity.

Figure 2 is a diagrammatic section along the surface II—II of the film 5 of Figure 1.

Figure 3 is a diagrammatic view of one form of our invention as embodied in a sound recording instrument.

Figure 4 is a diagrammatic view of one form of our invention as embodied in a sound recording instrument of a type different from that represented by Figure 3.

Figure 5 illustrates, in a form greatly exaggerated for clarity, the effects of refraction and diffraction in connection with a slot and a glass or other cover therefor.

Figure 6 is a diagrammatic representation of the application of one form of our invention, including an optical element, to a recording apparatus.

Figure 7 shows one means for cleaning the slot.

Figure 8 is a section on the line VIII—VIII of Figure 7.

Figure 9 is a diagrammatic representation of one form of our use of converging light in a recording apparatus.

Figure 10 shows one form of film gate as employed by us and Figure 11 is a diagrammatic representation of a substitute therefor.

Figures 12, 13, and 14 show details of a slot structure which we may employ.

Figure 15 shows means employed by us to maintain a light source at a constant temperature and point of incandescence.

Throughout the drawings and specifications, like characters apply to like parts. For the purpose of greater simplicity, like parts which are duplicated in various embodiments of our invention receive the same reference numerals except where clarity demands otherwise.

In carrying out our invention, we employ light of a predetermined wave length. We select light of that particular rate of vibration which has the

photographic qualities which are desirable for the particular result which is to be obtained. For example, when we select light from the visible spectrum, we employ monochromatic light of a selected color or wave length, for the recordation of the photographic image representing the sound waves.

From among the many photographic emulsions which are available, we are not compelled to choose in accordance with the limiting requirements of white light but are enabled to use in each employment of our invention the photographic emulsion which is best suited to the requirements of the particular conditions then applying and to employ in each instance that particular form of light which will be best suited to the particular emulsion deemed most suitable.

We select the developer for the latent image so implanted upon the selected emulsion by use of light of a selected wave length with due regard both to the particular characteristics of the particular emulsion and its reactions to the selected wave length and also to the peculiar demands of that portion of the film bearing the pictorial image as well as of that portion of the film bearing the sound image, in case both images are implanted upon the same strip. Thus it will be seen that we choose that particular combination of light, emulsion, and developer which will result in the most satisfactory sound and pictorial images under the given conditions.

In present common practice, polychromatic light, ordinarily spoken of as white light, is employed in apparatus using visible light for the electrical recordation of sound. Even with the use of a better photographic technique than is now common, polychromatic light would still cause many of the difficulties to which reference has already been had and will later be made.

For purposes entirely different from those embraced within or pertinent to our invention, it has been proposed to employ visible colored images for use as sound records. We do not use colored images as part of or in carrying out our invention of sound recordation. We use what is ordinarily known as colored light, but the latent images produced thereby, when rendered stable and visible by development, are what are known as black and white. They have none of the characteristics, requirements or purposes of colored images or photography. It will therefore be understood by those skilled in the art, that our invention does not require the use of the special and expensive films and apparatus, which have been proposed to be used for purposes different from our own, nor are we limited by the many photographic and practical difficulties associated with the use of so called colored films.

When reference in this specification or in the claims which a part hereof is made to "black and white" films, it is understood that such terminology is used with the meaning common in the motion picture art. Such "black and white" films may be colored by tinting or toning or any other similar process, whether carried on as supplementary to the regular development and fixing or otherwise. Moreover, the term may be used to include films which are made upon a base which is colored or tinted, provided the emulsion used thereon is one of those ordinarily associated with the making of black and white images if used with an ordinary white or gray base. It will be understood, of course, that when it is desired to use color for the pictorial portion of the film, our process may be applied to that portion

of the negative which is reserved for the symbols representing sound.

It will be noted in the subjoined claims that the step of moving the film, or means for moving the film, is not specifically included, although, as well known to those skilled in the art, and as is stated herein, sound is ordinarily recorded upon a moving film. Such omission in the claims of an obvious step or means is to avoid encumbering the claims with unnecessary words, since, wherever necessary, the inclusion of this obvious step or means will be understood.

In this specification, we often make use of the older term "slot" as designating the aperture which restricts the light reaching the film, but it will be understood that that term is to be taken as synonymous with the word "slit", as used elsewhere in the specification and in the claims.

The processes of the electrical recordation of sound upon a photographic film or similar light sensitive surface are of course well understood. The film or other light sensitive material is moved continuously at a uniform speed and upon it, generally through a slot, a light is projected, varying in accordance with the amplitude of the sound waves which are being recorded. Thus there is imprinted upon the light sensitive surface a series of images the photographic density of which varies in accordance with the variations of the sounds which are being recorded. The resulting images may appear to the eye to be a series of lines of varying intensity. These lines in the negative indicate by means of greater density the nodes of the sound waves and by less density the anodes of the sound waves, or, in case of the use of photo-electric cells, of a certain less usual type to control the fluctuation of the light, the reverse is true.

As a matter of convenience, it is to the above indicated method of sound recordation that reference will most often be made. It will be readily understood, however, that our invention is equally applicable to any form of sound recordation which depends upon the implantation of photographic images upon a light sensitive material, whether, for example, such images take the forms commonly known as variable density or variable area or any other form.

Figure 1 illustrates in a much exaggerated form the edge diffraction which is caused by passing polychromatic light through a narrow slot of the type commonly used in the art. The degree of diffraction which results from passing white light over an edge is directly proportioned to the lengths of the several waves which make up the light. Thus the rays of the longer wave lengths are diffracted to a greater extent than are those which are of lesser amplitude. In Figure 1, 1 represents a beam of polychromatic light of which 2 is the axis.

In this and many of the following drawings, for convenience we show the light as a straight line such as 1. It will be understood that, except as definitely stated, we do not limit ourselves to an optical system of any particular nature. The light may be projected, by any suitable optical system, in the form of parallel, divergent or convergent light. If desired, a mirror or other reflecting element, not shown, may be employed behind the light source. This light in passing through the opening 3 in the aperture plate 4 is diffracted in accordance with the wave lengths of its component parts. Thus the infra-red rays 6 and 6' show the maximum diffraction, the visible red rays 7 and 7' the next largest degree of dif-

fraction, the yellow rays 8 and 8' a lesser diffraction, the blue rays 9 and 9' the least amount of diffraction of the visible rays and the ultra violet rays 10 and 10' the least diffraction, the degree of diffraction of the sub-primary colors not being 5 shown.

As these rays of varying wave lengths fall upon the film 5, as is well illustrated in Figure 2 of the drawings, there are transverse bands of the light sensitive emulsion which are subjected to 10 rays of different colors. Every light sensitive emulsion has varying degrees of sensitivity to different colors. As a result of such varying sensitivity, while the entire portion of the emulsion between the lines 11 and 11' is acted upon 15 with approximate uniformity by the white light, the bands from 10 and 10' to 6 and 6', both inclusive, are acted upon in degrees varying according to the sensitivity to color of the particular photographic emulsion which is being used at 20 the time. As a result the portions of the entire line or mass which lie between 11 and 6 and 11' and 6' respectively are lacking in uniform photographic density, the portion between 11 and 11' being more nearly uniform. In other words, the 25 edge is not clear and straight. It is in effect ragged and "muddy". As a result, when a reproduction of the photographic image which is bounded by such an edge is used to actuate a photo-electric cell in the reproduction of sound, 30 what the auditor hears is likewise unclear, "muddy" and blurred. It will be readily recognized that any blurring of a recorded photographic image caused by such diffraction will result in a corresponding blurring of the sound 35 which is reproduced therefrom.

We have found that much of the difficulty in the past blamed generally upon "diffusion", and even photographic "grain", is in reality due to the lack of a correct photographic definition caused 40 by fringing colors, which in turn are the result of diffraction as stated above.

It will be readily understood that the more narrowly the slot is restricted in size, the more pronounced will be such imperfections.

In Figure 3 we show diagrammatically one embodiment of our invention applicable to a sound recording system such, for example, as one which employs an immovable light supplied by an electric current varying in accordance with the amplitude of the sound waves to which a diaphragm is subjected.

In Figure 3, the intensity of the light at source 12 in operation is constantly varied in accordance with the amplitude of the sound waves which are being recorded. Any one of the many well known devices to accomplish such purpose may be employed, as for example a microphone 13 connected with any suitable type of current controlling device indicated generically as 13'. Since the method of controlling the variations of the light source 12 in accordance with the sound waves is well known and forms no part of the present invention, it is neither described nor claimed.

The light 1 emitted by source 12, we pass through an appropriate color filter 14, the slot 3 in the aperture plate 4 and on to the film 5. Since the optical system, and the method of feeding the film form no part of the present invention and since any of several well known optical systems and film feeding methods may be employed, we do not describe or claim them.

The exact filter to be used will depend upon the photographic characteristics of the emulsion

selected. It will be readily understood that with the use of any monochromatic light all of the area of the film which is exposed or illuminated at the same instant will be of practically uniform density. For example, if we elect to employ light of approximately 4000 Angstrom units, we will use a filter 14 adapted to prevent the passage of all light other than such as will register between 8 and 9', inclusive, as shown in Figures 1 and 2. The image so created upon the film will have sharp demarcation along the lines separating band 8 from band 8 and band 9' from band 8'. That is, each illuminated or exposed area will be clearly and sharply defined and its so called photographic contrast great. Irrespective of the type of monochromatic light employed, the sharpness of differentiation or contrast will be increased over such as obtained with polychromatic light and the "raggedness" caused by the use of such light largely eliminated. It should be noted, however, that the relative excellence of the result will depend upon the selection of the wave length particularly appropriate to the photographic emulsion selected. In recent practice, in order to overcome difficulties caused by the so called "grain" of the emulsion, relatively slow emulsion, such as, for example, those of 120 according to the rating of Hurter and Driffield, have been recommended for sound films. By the use of photographically active wave lengths, such as for example those in the vicinity of 4000 Angstrom units, we secure with such a slow emulsion in a relatively short period of exposure the same results as others secure in a much longer and hence impractical period of exposure.

It will be understood that instead of using rays of one wave length only, we may employ rays of a group of related wave lengths.

In carrying out our invention we may simultaneously record the images representing sound upon the same film as that upon which the images representing action are recorded. Or we may make records of each series of images upon different films and subsequently impose the images representing sound upon an unoccupied portion of the film bearing the original images representing action. Or we may make separate record or negative films for the sound and action images and duplicate both such series of images upon different portions of one positive film.

If we use a common record or negative film for both sound and action images, as is shown for purposes of illustration in Figures 3 and 4 of the drawings, we may provide a camera lens C L through which light 1' from the action or scene being recorded is focussed through the aperture 3' upon the film 5. It will, of course, be understood that a certain portion of the film is reserved for the action images and another separate portion for the sound images, the respective apertures 3' and 3 being so designed as to direct the light beams 1 and 1' upon the appropriate portions of the film.

In those cases in which the sound and pictorial records are placed upon the same film, we may prefer to use an emulsion rated between 120 and 200 according to the scale of Hurter and Driffield. An emulsion of a speed of 180 upon that rating may be taken for purposes of illustration.

For an emulsion of such a speed, with the latent image of the sound record produced by monochromatic light, as for example that of approximately 4000 Angstrom units, and the pictorial portion produced by polychromatic light, we prefer to use glycine, known as gamma oxyphenyl

or as gamma oxyphenyl-amido-acetic acid, as the developing agency. Under such conditions, glycine will produce the necessary contrast in the sound image and at the same time build up the half tones of the action image. It will be readily understood by those skilled in the art that for pleasing results in reproduction the sound images require great contrast and the action images full gradation. If, however, polychromatic light is used for the sound images, the glycine development would tend to reduce the contrast in the sound images to a point which will result in unsatisfactory reproduction. If a hydrochinone developer is used, the sound image made with light of a wave length of 4000 Angstrom units would be satisfactory but the pictorial image, which is of course always recorded by polychromatic light, would be unpleasantly harsh. If a hydrochinone developer is used with a sound image made by polychromatic light, a period of development is necessary in order to secure proper contrast in the sound image which will still further increase the unpleasant harshness of the pictorial image.

The use of glycine is desirable also because it tends to reduce the grain. As is well known in the art, a slow emulsion has less grain than a more rapid one. Hence we prefer to use as slow an emulsion as is consistent with the demands of the pictorial image. Only with the use of monochromatic light is it possible to secure, in a way practical in sound recordation and reproduction, the use of both of these factors, namely a relatively slow emulsion and glycine development, which tend to eliminate the difficulty caused by grain.

In glycine development, the following stock solution may be prepared:

Water, H ₂ O	32 ounces
Sodium sulphite, Na ₂ SO ₃ , anhydrous	360 grains
Glycine, C ₆ H ₅ OHNHCO ₂ H	120 grains
Sodium carbonate, Na ₂ CO ₃ , anhydrous	360 grains

The chemicals should be dissolved in the above order. The water should preferably be of a Fahrenheit temperature between 100 and 120 degrees.

For use with the emulsions of the speed stated above, such stock solution may be diluted at the ratio of one part stock solution to three parts water. The film may be developed for thirty minutes, preferably at about 65 degrees Fahrenheit. After such development, the usual steps of washing, fixing, and final washing may be taken.

We prefer to keep the film totally immersed during the entire period of development in order to minimize oxidation fog. We have found that the elimination of such fog is an important item in securing clear and sharp sound images. Glycine is a developer which produces a minimum of such fog, but to prevent the possible formation of such fog, we may prefer to use a bath of pinakryptol green, in a dilution of one part to five thousand parts of water, before the development as by the use of glycine.

In those cases in which the sound images are to be recorded alone, without pictorial images upon the same film, we may prefer an emulsion rated on the Hurter and Driffield scale between 70 and 120. Excellent results may be obtained with an emulsion of such a speed of 40 for example. With any such slow emulsion, with no latent pictorial image thereon, we may use any so called contrast developer, such as hydro-

chinone, such as commonly known and used in the photo-engraving art.

It will be understood that we do not restrict ourselves to the particular formulae, methods, chemicals, or emulsion speeds stated above, but that we state the same for purposes of illustration.

For purposes of further illustration, it may be assumed that we wish to make a combined sound and pictorial record of waves breaking upon the shore of the sea. In order that we may secure full color and gradation values, we may prefer to use an emulsion having the color sensitivity commonly known as panchromatic together with a filter for the pictorial portion of the film. Such a filter may be of a yellow color and of the type commonly known in the photographic art as K3. For the sound image, we may prefer to use a light of approximately 4000 Angstrom units because such a light, in combination with a panchromatic emulsion, produces great contrast. The polychromatic light, modified as is well known in the art by the K3 filter, produces an image which is soft and pleasing. Glycin development of such a film gives satisfactory results in both portions. In this case, however, with the use of panchromatic film, we may prefer to use a preliminary bath of pinakryptol green diluted at a ratio of one part to four thousand 30 parts of water.

For the purpose of still further illustration, it may be assumed that it is desired to produce a combined sound and pictorial film under conditions which require a fast emulsion. The action 35 to be recorded, for example, may be rapid or light conditions poor and not subject to control as in a studio. An emulsion of a speed on the Hurter and Driffield scale of over 450 may be chosen. Under such conditions, a monochromatic light of 4000 Angstrom units may be too rapid in its action. In such cases, we prefer to use for the sound recordation a filter which will transmit light of a suitable wave length or group 40 of wave lengths as, for example, any wave or group of wave lengths between 4500 to 5800 Angstrom units, depending upon the particular emulsion employed. Thus we are enabled to give to the operator definite filters for use with 45 definite emulsions, rather than depending upon 50 adjustments in the field of the light source for the sound record.

It has been proposed in the past to make use of special emulsions which, after the images implanted thereupon have been developed and rendered visible, have peculiar characteristics of permeability by or absorption of light waves of particular wave lengths in combination with the photo-electric cell of particular characteristics in a sound reproducing instrument. It will be understood that we use regular stock photographic films known as black and white, which can be readily and cheaply obtained throughout the world, choosing such films, however, in accordance with the purely photographic characteristics thereof which are useful for the particular purpose set forth in this specification. Our choice of an emulsion of a particular speed is conditioned by the photographic characteristics of the latent images which can be implanted thereon by the use of light of a particular wave length, and the photographic characteristics of the visible and stable images which can be developed from such latent images. Although our invention can be applied to those types of apparatus in which separate films are employed for

the sound and pictorial records, it is also equally applicable to those types of apparatus in which one film is used to carry both such records. It will be readily understood that such a single film bearing both such records must be chosen, exposed, developed, duplicated and projected in accordance with all the requirements of both such records. As is made clear throughout this specification, our method is so adapted to create a single film which bears both types of records 10 thereupon.

Figure 4 represents diagrammatically the application of our invention to a sound recording device which depends upon a movable mirror of the so called "galvanometer", Pallophotophone, 15 or Hoxie type. A light source 15 of fixed intensity is provided, the light from which passes through a color screen 14 and impinges upon a movable mirror 16 the light rays from which pass through the slot 3 in the aperture plate 4 20 and impinge upon the film 5, in this case creating images which take the form of a wave line and create an oscillograph. The movement of the mirror 16 is actuated through the control device 13 and the microphone 18, which, being well 25 known in the art, are indicated merely for purposes of illustration, it being understood that they form no part of the present invention.

In recording devices as heretofore known, which have used polychromatic light, the slot 30 often has been constructed as narrow as possible and placed in contact with the moving film or separated from it by a thin cover or glass in an attempt to restrict the recorded image and thus overcome in some measure the results of 35 difficulties stated above. It has been extremely difficult to construct such slots, say those of a width of fifteen ten thousandths of an inch, or less, with sufficient accuracy, and, when constructed, to keep them free from particles of 40 dust, dirt, emulsion, and celluloid brought to them and deposited by the moving film. When cover glasses for the slot have been used with polychromatic light, difficulties caused by the varying degrees of refraction of the component 45 parts of white light have been added to those caused, as stated above, by the different degrees of diffraction.

It will be readily seen that by the use of our invention it is possible to employ a slot somewhat larger in size than has been common and free from contact with the film, since although the actual area of the exposure, or of exposed area to be projected for reproduction, may be somewhat larger than in the past, all of this 55 area is effective for the true recordation or reproduction of the image which represents the sound, none of the same being obscured in the twilight zone of fringing colors and impairing the quality of tone reproductions. Moreover, by the use of 60 rays of the shorter wave lengths, such as shown as falling between 8 and 8', 9 and 9', and 10 and 10', in Figures 1 and 2, it is entirely possible to eliminate sufficient width of the area of exposure to compensate in part for the small fraction of 65 an inch which the slot is removed from the film and its slightly larger width, and that without the employment of other means hereafter described. Generally speaking, however, owing to the edge diffraction of rays of any length, the 70 recorded image, from the larger slot so spaced, with the one of parallel or divergent light, will be slightly greater than the area of the slot.

It will be understood, also, that under our invention cover glasses can be employed without 75

the disadvantages arising from the different refractive characteristics of the component parts of polychromatic light.

This phase of our invention is indicated in Figure 5 in a form much exaggerated. 21 is a glass cover for the slot 3 cemented to the aperture plate 4. With the use of polychromatic light, only those portions of the film lying between 10 and 10' will receive or project an image without "muddiness" due to color aberration caused by diffraction and complicated by refraction.

By reason of the impinging of light of varying photographic effectiveness due to varying colors, 15 along the edges of the normally exposed line or mass upon the film, various aberrations occur in the resulting record film. These aberrations result in an incorrect reproduction of the originally recorded sound. As is well known, glass or other 20 similar surface 21 will refract all rays which strike it save those which are at right angles to its plane. Upon emergence, these refracted rays will resume a course parallel to their normal course. In Figure 5, the dotted lines show 25 the course which for purposes of illustration it is assumed these rays would take were it not for the refraction caused by the introduction of a substance such as 21. The refraction caused by 21, however, caused them to take the courses 30 illustrated by the solid lines. The boundaries between each color zone diverge as before, but these boundaries are brought nearer to the optical axis 2 thus reducing the zone 10 to 10' which represents the area free from color aberrations. 35 Ultra violet rays do not pass the glass 21, but if quartz were used, for example, the refraction would be similar in kind although different in degree to the refraction of visible rays as described above.

40 With the use of monochromatic light, however, say of 4000 Angstrom units, for purposes of illustration, the image will be restricted to the area lying between 9 and 8' and all of it will be true because of uniform density. Thus the film in 45 position 5 in Figure 5 with monochromatic light will receive an image, all of which is effective and true, which is not greatly if any enlarged over that of the image of the film in polychromatic light in position 5', much of such latter image 50 being ineffective and untrue.

Other preferred embodiments of our invention, however, make it possible to use a relatively large slot, run the film out of contact with it, and photograph an image which is relatively very 55 much smaller than the area of the slot. We accomplish this result either with or without the introduction of optical elements, and with the use of light of a selected wave length or group of wave lengths.

60 According to one of these embodiments of our invention, as is clearly shown in Figure 6 of the drawings, we introduce a suitable optical element 22, such as for example a positive lens of the type generally known in the optical art as "apochromatic", between the slot 3 and the light sensitive surface 5. We project light from the source 12, varied as previously set forth by the control element 13' from the microphone 13, or in any other suitable manner, through the filter 65 14, which may be chosen at will by the operator to suit the particular photographic requirements involved, through the slot 3 in the aperture plate 4 and through the lens 22 or other suitable optical element, upon the light sensitive surface 5. Thus by the use of monochromatic light we pro-

ject an image of the slot which is in no way affected by the aberrations common to white light and which is therefore reproduced upon the photo-sensitive surface 5 without loss of integrity. As is well known in the optical art, the size of the image projected upon the light sensitive surface can easily be controlled by the selection of a lens of the focus suited to the mechanical requirements and by focussing the image with this lens, according to the well known law of conjugate foci. Thus, by use of monochromatic light, it is possible to create upon the photo-sensitive material a satisfactory slot image appreciably smaller than the slot from which it is projected. By the employment of such means it 15 is apparent that the photographic intensity of the light 4 delivered upon the film 5 may be limited to a larger or smaller area as may be found desirable in the recordation of any desired sound upon the film 5. It is apparent that the intensity 20 of the light at any given point will be increased at the surface of the film as the area of the image is decreased and the rapidity of the photographic action of the beam of light will be increased accordingly. It is likewise apparent that 25 the recordation of the images so produced upon the film 5 through the optical element 22 may be made to vary in type limited only by the capacity of the emulsion employed to receive and record light effects upon minute areas of light 30 sensitive substances.

It is apparent that the ability so to record tonal variations in very great detail and almost microscopic size will render possible a vastly increased range of tonal recordation and likewise a notable 35 improvement in the detail of recorded sound.

It is also apparent that the increased intensity of light available for delivery at the surface of the film 5 through the means described will render possible the use of whatever less photographically active rays of light and photographically slower emulsions which may be deemed desirable because of the so called "grain" or other photographic difficulties, all of which above advantages, methods and means are such as will be 45 fully known to and understood by those skilled in the art without further description or explanation in detail.

The slot 3 may be constructed under our invention sufficiently large so that accuracy of 50 manufacture is possible without undue cost and so that it can be kept clean.

According to one embodiment, as is clearly shown in Figures 7 and 8, of our invention, the slot, wherever disposed and of whatever type, 55 may be kept clean throughout the entire operation of the apparatus by the provision of a draft of air, indicated in Figure 7 by the arrows, forced upwardly through a tunnel 29 by a fan 30 fixed in the housing 31, the entrance thereto being 60 suitably protected by dust-retarding material 32. A baffle plate 33 is so placed as to deflect the air current downwardly, as shown by the arrows in Figure 7, through the slot 3. Power to operate the fan may be applied from the motive power 65 of the film feeding apparatus, not shown, through the shaft 34 and the gear 35, which may engage a suitable gear of such apparatus.

Another embodiment of our invention makes it possible to secure many of the results above set forth, but without the use of special optical elements.

Thus, as set forth above and illustrated in Figure 9, in a recording apparatus, we may provide a variable light source 12, actuated by the con- 75

trol element 13' or like means and the microphone 13. Such variable light passes through the filter 14 and is condensed by the lens 41 of any suitable design. A mirror, not shown, may be provided if desired, as is well known in the art. The converging light 1 passes through the opening 3 in the plate 4 and, at or about its focal point, impinges upon the film 5. The slot 3 may be made somewhat smaller than the cone or wedge of light which it is desired to use for exposing the film 5 so that stray rays, illustrated in Figure 9 as 1', may be arrested.

As is illustrated more in detail in Figure 10, one preferred form of gate for films carrying sound records may consist of two transparent plates with no physical aperture whatsoever. In the gate shown in section 43, the portion 45 along which the image bearing portion of the emulsion-bearing side of the film travels, is slightly relieved, as is common in the motion picture art, the edges of the film bearing upon the raised portions 46 and the section 42 which bears against the film opposite to section 43 is completely flat and is held in position by springs 44 as is well understood in the art. When we make use of a monochromatic visible ray, the portion 47 of the plate 43 which is opposite the sound image carrying portion of the film is left transparent, but the remainder, left without cross markings in Figure 14, which is opposite the pictorial portion of the film and its edges, is silvered.

If for use with an optical system such as shown in Figures 6 or 9, such transparent portion may be of relatively long length, as shown, but, if a slot image is not focussed, such portion may be reduced in size to the dimensions of a so-called "optical slot". If desired, such transparent portion 47 may be so formed that it permits the passage of rays of the predetermined length only, and the filter 14 omitted.

Since it is inherently strong, is available in thin sheets, and for still further reasons which will be later apparent, the plates 42 and 43 may well be made of plane quartz although we have found glass practicable. It will be readily understood that since there is no aperture or slot across which the film travels, the problem of dust and dirt is overcome.

In the various exemplifications of our invention which have been set forth, the gate structure above described may be used, or any other suitable gate may be employed. In recording instruments making use of specific wave lengths, the back plate 42 of the above gate may also be silvered.

With the use of monochromatic light, however, as is illustrated in Figure 11, it is not always necessary to use a film gate of any kind for the exposure of the portion of the film bearing the sound symbols.

As is shown in Figure 11, the film 5 is fed continuously and positively as with positive engagement between its perforations and continuously rotating sprocket wheels 48 and their idlers 49. The sprockets 48 and their idlers 49 hold the film reasonably flat. Unless the film is very old and shrunken so that it tends to curl at the edges, this mechanism holds it sufficiently flat at the point at which the light strikes it so that a minimum of sound distortion is caused by a distortion of the light waves caused by the film being out of plane. Much of the difficulty which under present practice is attributed to this lack of proper plane evidently is due to the variations in

refrangibility of the several wave lengths composing white or polychromatic light.

According to one preferred embodiment of our invention, we employ ultraviolet light for any and all of the purposes above set forth in connection with visible monochromatic light. Ultraviolet light possesses the advantages which we have stated for monochromatic light in the visible spectrum and in addition shows less diffraction than any of the wave lengths of the visible spectrum and is furthermore extremely active photographically. In carrying out our invention by means of the use of ultraviolet light, we employ any suitable light source encased in quartz, or a light source which will emit visible and ultraviolet light under normal atmospheric conditions, such as, for example, the electric arc and the so called Nernst lamp. In carrying out our invention in accordance with this exemplification, we use a light source 12 of some such type as we mention above in such structures as those diagrammatically represented in Figures 3, 4, 6, and 9, and in the manner described in connection therewith. In every instance in which a lens or other similar optical element is employed in connection with ultraviolet light it must of course be constructed of quartz, as is well known in the optical art.

In order to combine aperture plate and filter, with the use of ultraviolet light, we may employ the aperture plate which is illustrated in Figures 12, 13, and 14. Two pieces of very thin glass or metal 56, separated sufficiently to form a slot 57 of the requisite width, are placed between two pieces 58 of plane quartz. It is often found easier to cement two such pieces of glass or metal in the proper position than accurately to cut a slot of this extreme narrowness in either glass or metal or to draw it upon a silvered surface. All of one surface or more of the quartz as required is silvered in order to stop all visible rays. As is illustrated in Figure 14 of the drawings, it is possible to limit the ends of the slot as desired by filling them with some material, such as asphaltum 59, which is opaque to the particular ray which is being employed. The accuracy of the ends of the slot in most types of apparatus is not as important as is that of the sides.

To secure improved and stable translation of sound images into light images, the theoretically constant light source may be maintained at a point which is actually constant, or approximately constant, as is illustrated, for example, in Figure 15 of the drawings. Obviously the difficulties caused by the change in color of the light caused by the fluctuations of the light source is removed by the use of monochromatic light. A further embodiment of our invention prevents material change in light intensity, such changes causing analogous difficulties.

A common cause of change in intensity of the theoretically constant light source is found in temperature changes which decrease or increase the degree of incandescence of the light element. The common expedient of warming the light source by turning on the current in advance of its use does not meet the difficulties caused by later changes in temperature caused by conditions which later developed. We have found that the opening of a door or window in a room in which apparatus is being used will change the visible characteristics of the light. The means shown for example in Figure 15 definitely controls the heat of the theoretically constant light source.

A light source shielded and controlled as is here set forth may be used as desired in any or all of

the previously described exemplifications of our invention. The arrangement herebelow described is of particular usefulness under any conditions under which an approximately constant light source is desired. Broad claims to this phase of our invention will be found in our parent application.

In one embodiment of our invention, we may place the light source 12, which for example may be an incandescent globe of any desired type, in a chamber with double walls such as 68 and 61, and preferably with an air space 62 between them. Fresh air is forced into this chamber 62 by a fan 63 rotative upon a shaft 64 to which is attached a pulley 65, and such air takes the direction shown by the arrows. The pulley 65 may be driven in any desired way, not shown. Through the opening 66 past the baffle plate 67 the fresh air is directed into the inner lamp chamber. The wall 68 being preferably of a heat conductive material, the fresh air, while considerably cooler than the body of air in the chamber, is not of a temperature sufficiently low to cause a drop in the incandescence of the lamp. The heated air leaves the chamber through the vent 68 in the top, which is protected by baffle plates, not shown, as is well known in the projection art, to prevent the escape of objectionable light.

Under some conditions the fan 63 may be dispensed with, sufficient circulation of air being obtained by the heat generated within the chamber.

Light is passed from the source 12 through the optical element 69 which may form the window, as it were, of the lamp chamber. Such optical element may be a plate of plane glass or quartz, merely to complete the enclosure of the chamber, or it may be a suitable condensing lens or filter. A mirror or other reflecting surface 70 may be provided.

In order positively to maintain the lamp 12 at a given point of incandescence by holding the temperature of the chamber at a predetermined point, a thermostatic element 71 may be provided which, through an appropriate electrical means, controls the amount of current which is permitted to flow into the heating units 72 which may be placed within the chamber.

The thermostatic control of the circuits of the heating units 72 may be accomplished in any of various well known ways. For example, the thermostatic element 71 may be in circuit with the magnetic element 73 which determines the movement of the wiper arm 74 so that it places more or less of the resistance 75 in circuit with the heating elements 72, thus determining their activity.

It will be understood that we do not limit ourselves to this type of control unit and refer to it merely for purposes of illustration.

In order to compensate for changes in incandescence of the light source which might be brought about by changes in the temperature of the lamp chamber, or lamp house as it is generally termed in the motion picture art, we may regulate the amount of current reaching the lamp in accordance with the temperature of the immediate vicinity of the lamp. Such means may be employed independently of the heat maintaining means just described, or in conjunction therewith. For simplicity, we illustrate this phase of our invention in Figure 15, which also illustrates such heat maintaining means.

A thermostatic element 76 may be provided

which controls the amount of current which is permitted to flow into the light source 12. As is later set out in further detail, such control is exercised within restricted limits. The thermostatic control of the circuit supplying the source 12 may be accomplished in any of various well known ways. For example, the thermostatic element 76 may be in circuit with the magnetic element 77 which determines the movement of the wiper arm 78 so that it places more or less of the resistance 79 in circuit with the light source 12. The range within which the current reaching the lamp is permitted so to fluctuate is very small. When a light source, particularly an incandescent light source, is operated reasonably near its point of optical efficiency, a relatively small fluctuation in the current reaching such source will have relatively great effect in the intensity of its light output. It will be understood that since uniformity and not intensity is desired, it is preferable to burn the lamp at a point well below that at which injury to the filament is likely. We prefer that the maximum current permitted to reach the lamp by the resistance 79 be sufficiently restricted so that even when the filament is cold such maximum current will not be dangerous to the life of the filament.

As an additional safeguard, to prevent overloading of the circuit supplying the light source, we may place in such circuit an automatic circuit breaker 80, or other similar device, or the light source 12 may be fed direct from a battery or the line. This control element will positively prevent any amount of current, over the predetermined maximum, reaching the light source 12.

In those cases in which the heating elements and the means for the control of the circuit of the light source are jointly used, it will be readily understood that the usefulness of the latter means generally will be greater in the early stages of any period of operation. After the temperature of the lamp chamber has been brought to the desired point, it will generally be so maintained by the heating elements alone.

It will be readily understood by those skilled in the art that the joint operation of these two means involves no conflict. From the time of beginning operation until the temperature of the lamp chamber reaches the predetermined point, the thermostatic element 71 will operate gradually to increase the amount of resistance 75 in circuit with the heating elements 72 and so render them less and less active. From that point onwardly, the fluctuations of current in the circuit feeding the heating elements 72 will be such as are necessary to maintain that predetermined point of temperature. It is understood that the ventilating device such as heretofore described when the heating units 72 are entirely inactive will prevent the temperature of the chamber from reaching a point higher than the predetermined point.

When operations begin, all resistance 79 will be out of the circuit feeding the light 12, it if desired being protected against overloading as by the element 80. As the temperature of the chamber increases, the amount of such resistance 79 in circuit with the light source 12 gradually increases until the entire amount is in circuit when the temperature reaches the predetermined point. Should such temperature rise still further, as is not contemplated owing to the above described ventilating system, there would be no change in the amount of such resistance 79 in circuit. Should such temperature fall, the

amount of resistance 78 would be decreased until the light source 12 receives the entire amount of current delivered from the line as through the protective device 80. The range of the resistance 78, it will be understood, is carefully limited in accordance with the closely limited range in which current fluctuations occur.

It will thus be apparent that the method and construction above described provide extremely simple means whereby sound waves may be accurately and effectively translated into photographic images.

Other advantages have been referred to throughout the specification from which it becomes apparent that different embodiments of the invention may be made within the scope of the inventive disclosure hereof.

We claim:

1. The method of recording sound which consists in the exposure of photo-sensitive material to light of approximately 4000 Angstrom units varying the light for implanting latent images thereon in accordance with the variation of the sound which is being recorded, and developing said latent images into black and white visible images.

2. The method of recording sound which comprises the exposure of a light-sensitive material of a speed between 120 and 200 according to the rating of Hurter and Driffield to light of a wave length of approximately 4000 Angstrom units, which light varies in accordance with the sound which is being recorded.

3. The method of recording sound which comprises projecting light which varies in accordance with the sound which is being recorded which light is of a predetermined wave length upon photo-sensitive material of a speed between 120 and 200 according to the rating of Hurter and Driffield whereby latent images are implanted thereon and developing said images with a developer which includes glycin.

4. The method of recording sound which comprises projecting light which varies in accordance with the sound which is being recorded which light is of a wave length of approximately 4000 Angstrom units upon a photo-sensitive material of a speed between 120 and 200 according to the rating of Hurter and Driffield whereby latent images are implanted thereon and developing said images with a developer which includes glycin.

5. The method of recording sound which comprises projecting light which varies in accordance with the sound which is being recorded, which light is of a predetermined wave length, upon photo-sensitive material of a speed of between 120 to 200 according to the Hurter and Driffield rating whereby latent images are implanted thereon, reducing oxidation fog in said material, and rendering said latent images visible and stable by developing said material according to a formula which includes glycin.

6. The method of recording sound which comprises passing light through a slit and upon light sensitive material, varying light from said source in accordance with the sound to be recorded, and limiting such light to rays which vibrate at substantially the same rate thereby minimizing the effects of chromatic dispersion caused by said slit.

7. The method of recording sound which comprises the exposure of light-sensitive material to light which varies in accordance with the sound which is being recorded and limiting such light to ultra violet.

8. The method of recording sound which comprises positioning a source of light within a chamber, varying said light in accordance with the sound which is being recorded, directing light from said source upon a light sensitive film, and supplementing the heat emitted by said light source for maintaining the temperature within said chamber at a predetermined level so that the color characteristics of light emitted by said source will remain substantially constant.

9. The method of recording sound which consists in passing a beam of light falling within a predetermined range of wave lengths upon light sensitive material, varying said light in accordance with the sound which is to be recorded, and maintaining the source of said light at such predetermined level throughout the sound recording operation.

10. The method of recording sound which consists in projecting light from a source the wave length of which is maintained at approximately 4000 Angstrom units upon a light sensitive film and varying said light in accordance with the sound to be recorded while maintaining said light at approximately 4000 Angstrom units.

11. The method of recording sound which consists in continuously operating a light source positioned within a chamber, varying said light source in accordance with the sound being recorded, causing said light as so varied to fall upon a light sensitive film, thermostatically regulating the amount of current reaching said light source in accordance with the temperature of said light source for continuously maintaining said light source without unwanted fluctuations, whereby the color emanation of said source impinging upon said light sensitive material remains constant, and rendering the images so produced stable and visible.

12. In apparatus for the recordation of sound, a source of light, a chamber in which said light is positioned, means for varying said light in accordance with the sound which is to be recorded, and means for supplying predeterminedly heated air within said chamber to maintain said light source at a predetermined level whereby the color emanation of said light remains unchanged so that the effective light output thereof is not subject to unwanted variations.

13. In apparatus for the recordation of sound, an electrical source of light, means for varying light from said source in accordance with the sound which is to be recorded, means for directing light from said source as so varied upon a light sensitive film, operable means for varying the amount of current reaching said light source, and means responsive to the heat generated by said light source for operating said current varying means.

14. In apparatus for the recordation of sound, an electrical source of light continuously operable, means for varying said light in accordance with the sound which is to be recorded, means for projecting said light upon a light sensitive film, and means effective to maintain the incandescence of said light source during its continued operation at a predetermined level of such character that the light emitted has a wave length of from 2800 to 4800 Angstrom units.

15. In apparatus for the recordation of sound, a light source, means for varying light from said source in accordance with the sound which is to be recorded, means for limiting the light to rays which vibrate at substantially the same rate, a slit, and means for focussing the image of said

slit as formed by light from said source as modified by said filter upon a light sensitive film.

16. In apparatus for the recordation of sound, a light source, means for varying light from said source in accordance with the sound which is to be recorded, means for limiting the light to rays which vibrate at substantially the same rate, a slit, and means for converging light from said source through said slit and upon a light sensitive film.

17. The method of recording sound which comprises modulating a light beam in accordance with sound which is to be recorded, passing said beam first through a color filter, second through a condensing lens, third through a slit, and thereafter upon light sensitive material, said filter serving to minimize the effects of chromatic dispersion which would otherwise result from the passage of light through said slit.

18. In apparatus for recording sound, a source of ultra-violet light, means for varying light from said source in accordance with the sound to be

recorded, means for passing a light sensitive film through light from said source, and means limiting the light which reaches the film to ultraviolet.

19. In apparatus for recording sound, a source of light of approximately 4000 Angstrom units, means for varying said light in accordance with the sound to be recorded, and means for passing such light upon a light sensitive film.

20. The method of recording sound which comprises passing light through a slit and upon light sensitive material, varying the light in accordance with the sound which is being recorded, and limiting such light to ultraviolet.

21. The method of recording sound which comprises passing light of approximately 4000 Angstrom units through a slit and upon light sensitive material and varying such light in accordance with the sound which is being recorded.

CARL LOUIS OSWALD.
WARREN DUNHAM FOSTER.
